(57) **CLAIM**

The ornamental design for a spittoon having a removable funnel, as shown and described.

DESCRIPTION

FIG. 1 is an exploded side view of a spittoon having a removable funnel showing our new design;

FIG. 2 is a top view of the removable funnel of FIG. 1;
FIG. 3 is a top view of the receptacle portion of FIG. 1 with the funnel removed;

FIG. 4 is a bottom view of the removable funnel of FIG. 1;
FIG. 5 is a bottom view of the receptacle portion of FIG. 1;
FIG. 6 is an exploded perspective view of the spittoon of FIG. 1 showing the removable funnel and the separate receptacle portion;

FIG. 7 is a side view of the assembled spittoon of FIG. 1 with the funnel inserted into the receptacle portion;

FIG. 8 is a perspective view of the assembled spittoon of FIG. 1 with the funnel inserted into the receptacle portion;

FIG. 9 is an exploded side view of an alternative embodiment of a spittoon having a removable funnel showing our new design;

FIG. 10 is a top view of the removable funnel of FIG. 9;
FIG. 11 is a top view of the receptacle portion of FIG. 9 with the funnel removed;

FIG. 12 is a bottom view of the removable funnel of FIG. 9;
FIG. 13 is a bottom view of the receptacle portion of FIG. 9; and,

FIG. 14 is an exploded perspective view of the spittoon of FIG. 9 showing the removable funnel and the separate receptacle portion.

The broken lines on the surface portion indicate contour and not surface decoration.
